UNITED STATES PATENT OFFICE

167,317

BAKING DISH

Clarence L. Maish, Warsaw, Ind.

Application August 28, 1951, Serial No. 16,458

Term of patent 3½ years

(Cl. D36—2)

To all whom it may concern:

Be it known that I, Clarence L. Maish, a citizen of the United States, residing at 936 East Main Street, Warsaw, State of Indiana, have invented a new, original, and ornamental Design for Baking Dish, of which the following is a specification, reference being had to the accompanying drawing, forming a part hereof.

Fig. 1 is a top plan view of a baking dish, showing my new design;

Fig. 2 is a side elevational view;

Fig. 3 is an end elevational view; and

Fig. 4 is a bottom plan view thereof.

I claim:

The ornamental design for a baking dish, as shown.

CLARENCE L. MAISH.
